UNITED STATES PATENT OFFICE.

OLOF JONATHAN MELLGREN, OF GOTTFENBORG, SWEDEN.

INSULATING MEANS.

Application filed February 4, 1921. Serial No. 442,510.

To all whom it may concern:

Be it known that I, OLOF JONATHAN MELLGREN, a subject of the King of Sweden, residing at Gottenborg, Sweden, have invented 5 certain new and useful Improvements in Insulating Means, of which the following is a specification.

This invention relates to insulating of pipes or similar parts against high or low 10 temperatures and has for its object to provide a simple and reliable method for insulating such parts without need of specially trained workmen for carrying out the job.

Another object of this invention is to provide 15 means to use insulating materials of a powdered structure without mixing it with a moist binding material such as is the case with the plurality of powder shaped insulating materials hitherto known.

20 A further object of this invention is to facilitate the use of certain cheap materials which possess a rather high insulating effect but which have not been able to utilize before because of their structure having a non- 25 convenient feature for application upon the surface to be insulated.

It is known to preform materials for the insulating of pipes or the like against heat or cold in the form of cushions or plaits. Insulating 30 materials of a powdered structure must be silted up with a binding member whereupon the mass thus produced is applied upon the pipe or other part to be insulated like a mortar. Said forms of the insulating material, however, require a lot of 35 preparatory operation either for the manufacture of the cushions or plaits or for the application of the mortarlike material. Especially the last mentioned form of the insulating material is a very disadvantageous 40 operation partly on account of the fact, that the operation can be performed only on hot surfaces so as to enable the evaporation of the water in the mortar, partly depending 45 thereupon, that professionally skilled people must be used for the purpose and finally thereupon that plenty of time must be spent to wait for the drying of an already applied layer of the mortar-like mass before the next 50 layer can be worked.

This invention consist therein that powder shaped insulating materials are filled into hose-shaped coverings manufactured of a soft flexible material. The hose- 55 shaped bodies such filled with insulating materials then are wrapped round the object

which has to be insulated. It is advisable to dip the filled hose into water-glass or a similar solution in order to airtight close up the pores in the covering and further the hoses 60 when applied upon the pipe may be coated with some tightening means or be encircled with a bandage as hitherto is usual when insulating pipes or similar parts.

In the accompanying drawing there is diagrammatically shown an embodiment of the 65 insulating device.

Fig. 1 shows partly in section a hose-like covering filled with the insulating material,

Figure 2 a perspective view of a pipe insulated in accordance to this invention, and 70

Figure 3 a section of a pipe such insulated.

The powdered material which may consist of any suitable insulating material as for instance fine-ground bark of pine is filled 75 up in a hoseslike covering manufactured of a soft, flexible material as for instance linen or tricot cloth, whereupon the ends of the hose when filled are tied up in order to prevent the powder to escape. In Figure 1 the covering is indicated by reference figure 1. The insulating material by 2 and the ties at the 80 ends of the hose by 3.

It is to recommend, when insulating a pipe 4 (Figure 2), to apply the insulating hoses 85 in such a way, that no inactive interruptions arise for which purpose the hoses conveniently may be performed in such a manner, that outside the tied ends there is left an empty portion 5 of the hose, which when 90 joining the hose with another hose can be telescopically drawn over the end-portion of the adjacent hose, as shown on the right hand in Figure 1 where the joint is secured by means of a cord 6. In Figure 2 there is 95 shown how a bandage 7 can be wrapped round the pipe when insulated. As already mentioned this bandage then may be coated with a protecting material such as water-glass, oil-paint or any other suitable coating. 100

For the insulating of pipes of different sizes or for insulating against temperatures of different height there may be used hoses of different diameters. As, however, a too thick insulating hose is rather difficult to 105 wrap round the pipes and furthermore does not cover the pipes with a necessary uniformity, it is more suitable to manufacture the insulating hoses with an uniform, comparatively small diameter and, when necessary, wrap a plurality of such narrow hoses 110 outside each other. In this way the outer

layers of the hoses cover the interspaces between the inner turns of the hoses and thus a considerable tight insulating is attained.

If the hose-covering gradually should be 5 destroyed, for instance by coiling against the hot pipe-walls, such a fact, however, has no injurious effect upon the insulating capacity, inasmuch as the bandage 7 or the paint coating gives the whole an entirely tight outer 10 surface which prevents the powdered insulating material to escape or to be displaced, if the hose-covering should be destroyed.

Although the invention according to the title above refers to the insulating of pipes 15 or the like, I do not limit myself to objects which strictly speaking are to be reckoned as pipes. For instance the method and the de-

vice according to this invention can be applied for insulating of steam boilers, work-cylinders of steam-engines, compressors, 20 pumps or the like and also of boilers for treating of sulphite pulp or for other of technical apparatus.

Having thus described my invention and how it is to be performed what I claim is: 25

An insulating means ready to be applied upon a pipe or any other object to be insulated against high or low temperatures comprising substantially finely ground bark of pine, free from any binding ingredients and 30 enclosed within a flexible cover.

In testimony whereof I have affixed my signature.

OLOF JONATHAN MELLGREN.
